SHIELD

Harry W. Kulp and Martin C. Dellinger,
Lancaster, Pa.

Application December 3, 1932. Serial No. 645,596

7 Claims. (Cl. 81—3)

This invention relates to shields primarily intended for use in catching the removable keepers, keys or "horse shoes" commonly applied about the lower end of internal combustion engine valve stems of the poppet type to retain the valve springs on said stems.

The present invention is an improvement on our invention forming the subject matter of our Patent No. 1,776,159, granted Sept. 16, 1930.

In practice in using the shield shown in said Patent No. 1,776,159 and similar shields, it has been found that in some instances the keepers or "horse shoes" will stick very tightly in place on the valve stem even though the spring and its retaining cup have been raised to be well out of the way. This sticking of the keepers seems to be due, at least to some extent, to the oil having partially dried out or solidified to form a gummy cementing agent that firmly holds them in position. In such cases it is usual to press against them with a screw driver or similar tool so as to force them from position. In some instances it has been found that they have been stuck so tightly that the force exerted on the screw driver to shove them from position results in shooting them laterally inward, so that in such circumstances such keepers often fly over the top edge of the inner end portion of the outer wall or flange of the shield and drop downward into the crank case notwithstanding the use of the shield.

Our present invention has been evolved or conceived with the foregoing facts particularly in mind and has for its primary objects to provide a shield for this purpose with a supplemental outer wall or flange which may be raised after the shield is inserted through the usual access opening and which as raised will, together with the outer flange, constitute a composite flange of nearly double the height of the usual flange, whereby the shield may be inserted through a narrow space which would not accommodate the tool with the supplemental wall raised and yet have the advantage of the added height to the outer flange after the shield is inserted; to provide in such a tool means for operating said supplemental flanges or walls to raise and lower the operative portions thereof; and to provide automatic means for lowering the operative portions of said supplemental flanges or walls as the shield is opened and to automatically raise the same as the shield is closed.

In this application we show and describe only the present preferred embodiment of our invention simply by way of illustration of the practice

thereof, as by law required. However, we are appreciative of the fact that our invention is capable of other and different embodiments and that the several details thereof may be modified in various ways, all without departing from our said invention and therefore the drawing and description herein are to be considered as merely illustrative and not as exclusive.

In the accompanying drawing:

Figure 1 represents a perspective view of a shield embodying our invention;

Figure 2, a top plan view thereof;

Figure 3, a side elevation thereof, in closed condition;

Figure 4, a top plan view thereof, in open condition;

Figure 5, a side elevation thereof in open condition;

Figure 6, a sectional view on a line corresponding to line 6—6 of Fig. 2, the parts being illustrated in the positions they occupy when the members A and B are about half way between their extreme positions shown in Figs. 2 and 4 respectively; and

Figure 7, a fragmentary detailed view on the line 7—7 of Fig. 2, looking in the direction of the arrows.

Referring now in detail to the drawing, A designates one member of the shield; B, the other member of the shield, said members being lapped and pivotally connected by a pivot pin C, a coiled spring D being anchored and positioned by said pin C and having arms E which respectively carry at their extreme end portions hooks F to engage the respective outer side edge portions of the members A and B at cut-out or recessed portions G to force said members A and B toward each other to closed position under the action of said spring D. Each member A and B is provided with a rearwardly extending thumb piece or finger piece H extending to the rear of the pivot pin C, said finger pieces H to be pressed toward each other to open the members A and B and to be released to allow said members to move to closed position under the action of spring D. Each of said members A and B is provided with an outer edge wall or flange I and with an inner edge wall or flange J.

The parts specifically immediately above referred to and their interrelation are fully set forth and described in detail in said Patent No. 1,776,159, so that a more detailed description herein is not thought either necessary or desirable.

The improvements of the present invention

comprise two supplemental outer edge flanges or walls 1 respectively pivotally connected to the respective members A and B at their outer or rear end portions by any suitable means, such as pivot 5 pins 7 passing outward through vertical lugs 6 respectively integral with the respective members A and B, and through the outer or rear end portions of the respective supplemental flanges or walls 1, preferably receiving on their outer 10 end portions washers 8 and having their extreme outer end portions riveted over or upset against said washers 8. Each member 1 is formed with an approximately inverted and reversed L-shaped slot 2 about midway of its length to receive the 15 holding, guiding and stop fingers 3 respectively integral with and stamped and inwardly pressed from the respective outer edge flanges I of the respective members A and B. Each supplemental flange 1 preferably has the lower part of its 20 curved inner or forward edge portion cut away as indicated at 4 to avoid any possible binding against the inner face of the corresponding or the cooperating outer edge flange I, there being left in the extreme inner or front portion of each 25 element 1 a depending finger 5 extending substantially below the upper edge of the cooperating outer edge flange I and so preventing the bending or yielding inwardly of said supplemental flanges or walls 1 under the impact of a keeper 30 or "horse shoe" flying from position as forced loose as referred to.

To the rear of the respective pivots 7 the respective supplemental flanges or walls 1 have their rear end portions turned abruptly toward each 35 other, preferably at right angles to their adjacent portions, and have said inwardly turned portions formed with depressing or retracting or telescoping upper fingers 12 and raising or elevating lower fingers 14 spaced from each other by a slot 40 13, the respective slots 13 slidably receiving the inclined cams 10 preferably integral with flanges 9, which in turn are preferably integral with the respective members A and B, the member B being 45 arcuately slotted as at 11 to permit the passage therethrough of the lug 9 integral with member A.

In assembling the supplemental flanges 1 are first inserted in their corresponding members A and B, the horizontal upper portion of the slot 50 2 being fitted in registry with the corresponding lug 3 to receive the same, and said supplemental flange or wall 1 being thereafter shoved forward until the perforation in its rear portion is in registry with the perforation in the corresponding lugs 7, when the pivot pin or rivet 7 is passed through the registering perforations, the washer 8 applied and the ends of the rivet or pivot 7 headed over as usual. Thereafter the 55 two members A and B with their supplemental flanges or walls 1 mounted as above are fitted together with the flange 10 of the lug 9 of member B disposed in the slot 13 of the supplemental flange 1 pivoted on member A and the flange 10 of the lug 9 carried by member A similarly disposed in the slot 13 of the supplemental flange 1 60 carried by member B.

In use the finger pieces H are first pressed toward each other, forcing the portions of the members A and B on the other side or forward 70 of the pivot pin C to swing away from each other to open position. At the same time the upper faces of the cams 10 engage the respective opposed lower edge faces of the depressing fingers 12, so forcing said fingers and the rear portions 75 of the supplemental flanges 1 upward about the

axes of the pivots 7 and forcing the inner or front portions of said supplemental flanges 1 downward to their lowest positions as shown in Fig. 5. In this condition the forward portion of the tool is inserted about the valve stem or tappet and pressure on the finger pieces H is released, allowing the members A and B to move to closed position, as illustrated in Fig. 2, under the action of the spring D. In so moving the lower or under faces of the respective cams 10 will slidably engage the opposed upper faces of the respective lower fingers 14 and force the same downward about the respective pivot pins 7 and of course at the same time cause the inner or forward portions of the supplemental flanges 1 to rise, the upward movement of said forward portions of the supplemental flanges 1 being limited by the contact of the lower end edge of the vertical portions of the respective slots 2 with the respective opposed faces of the respective lugs 3.

In the assembled relation of the parts the respective lugs 3 will extend lengthwise of the respective supplemental walls 1 rearwardly appreciably beyond the rear edges or walls of the respective slots 2 and will lie substantially parallel thereto to hold the respective supplemental flanges or walls 1 in proper relationship to the respective outer edge walls or flanges I.

The cams 10 will preferably be of thin sheet metal of the same stock and thickness as the metal from which the members A and B are formed and preferably the upper and lower faces of each cam 10 will be parallel or substantially parallel to each other.

The exact construction and form of the slots 2 and cooperating lugs 3 are not of importance and indeed they might entirely be omitted.

The exact construction of the lugs 9, cams 10, and cooperating fingers 12 and 14 is not of importance considering our invention in its broader aspects, it sufficing if there be means provided whereby said supplemental flanges or walls 1 may be raised and lowered as desired in the use of the tool. Less broadly considered, the exact details of construction of the lugs 9, flanges 10 and cooperating fingers 12 and 14 is not of importance, it sufficing if there be provided automatic means for raising and lowering the supplemental walls or flanges 1 as the said members A and B are closed and opened.

In the drawing, Figs. 2 to 7 inclusive are drawn to exact full-size scale, from an actual commercial embodiment of our invention, and Fig. 1 was drawn from said commercial embodiment and is intended to be of the same size as said embodiment as viewed from the angle and distance from which said view was made, but said view being a perspective view there has been no attempt to adhere to exact scale in said Fig. 1.

Having thus described our invention, what we claim as new and desire to secure by Letters Patent is:

1. A device of the character described comprising a plurality of plates respectively having vertical flanges extending lengthwise and across the front end portions of the respective plates, a pivot pin extending through said plates and pivotally connecting the same, and a spring acting to swing said plates toward each other about the axis of said pivot pin to closed position, in combination with a pair of perforated lugs respectively integral with, and extending vertically from, said plates respectively, a pair of supplemental flanges respectively disposed substantially parallel to the flanges of their respec-

- 5 tive cooperating plates and having rear end portions bent inwardly in opposed relation to each other, means for pivotally mounting the respective supplemental flanges on the respective per- 80
forated lugs at a point in advance of said rear inwardly bent portions, said inwardly bent portions respectively being provided with upper depressing fingers and lower elevating fingers, the said upper and lower fingers of said portions being
10 spaced from each other by a slot, a pair of cam flanges integral with the respective plates and a pair of cams respectively inclined to the vertical endwise of the device and integral with said cam flanges, and respectively received in the slots
15 of the respective rear end portions of said supplemental flanges, said cams respectively slidably engaging the lower edge faces of the respective upper depressing fingers as the said plates are swung about their pivotal point to open position,
20 whereby said supplemental flanges are rocked about their points of pivotal mounting to depress their forward ends, and said cams respectively slidably engaging the upper faces of the respective lower elevating fingers as the plates are
25 swung about their pivotal point to closed position under the influence of said spring, whereby said supplemental flanges are rocked about their points of pivotal mounting to depress their rear portions and to elevate their front portions.
30 2. A device of the character described comprising a plurality of plates respectively having vertical flanges extending lengthwise and across the front end portions of the respective plates, means for mounting said plates for relative swing- 105
35 ing movement toward and from each other, and means normally acting to urge said plates toward each other to closed position, in combination with a pair of lugs respectively integral with, and extending vertically from, said plates
40 respectively, a pair of supplemental flanges having rear end portions bent inwardly in opposed relation to each other, means for pivotally mounting the respective supplemental flanges on the respective lugs at a point in advance of said rear 110
45 inwardly bent portions, said inwardly bent portions respectively being provided with upper de-pressing fingers and lower elevating fingers, and means respectively carried by the respective plates and moving therewith and respectively
50 operatively engaging one or the other of the re- 115
55 spective depressing or elevating fingers in accordance with the direction of relative movement of said plates whereby said supplemental flanges are rocked about their points of pivotal mounting.
60 3. A device of the character described comprising a plurality of plates respectively having vertical flanges extending lengthwise and across the front end portions of the respective plates, means for mounting said plates for relative swing- 120
65 ing movement toward and from each other, and means urging said plates toward each other to closed position, in combination with a pair of lugs respectively integral with, and extending vertically from, said plates respectively, a pair of sup- 125
70 plemental flanges respectively disposed adjacent to the flanges of their respective cooperating plates and having rear end portions bent inwardly in opposed relation to each other, means for
75 pivotally mounting the respective supplemental flanges on the respective lugs at a point in ad- 130
80 vance of said rear inwardly bent portions, said inwardly bent portions respectively being pro-
85 vided with upper depressing fingers and lower elevating fingers, and means carried by the re-
spective plates and operated by the relative move-
ment thereof to engage the depressing, or ele-
vating, fingers according to the direction of said
relative movement to cause corresponding rock-
ing movement of the respective supplemental flanges about their respective points of pivotal mounting.
90 4. A device of the character described comprising a plurality of plates respectively having vertical flanges extending lengthwise and across the front end portions of the respective plates, means for mounting said plates for relative swinging movement, and means urging said plates toward each other to closed position, in combination with a pair of supplemental flanges respectively disposed adjacent to the flanges of their respective cooperating plates, means for pivotally mounting the respective supplemental flanges on the respective plates, and means operated by the relative move- 100
95
100 ment of said plates to rock said supplemental flanges about their respective points of pivotal mounting.
105 5. A device of the character described comprising a plurality of plates respectively having vertical flanges extending lengthwise and across the front end portions of the respective plates, and means for mounting said plates for relative swing- 110
110 ing movement, in combination with a pair of sup-
plemental flanges respectively disposed adjacent to the flanges of their respective cooperating plates, means for movably mounting the respective supplemental flanges on the respective plates for movement with relation to the opposed faces of the respective flanges of said plates respec- 115
115 tively, and means operated by the relative move-
ment of said plates to cause corresponding move-
ment of the said supplemental flanges.
120 6. A device of the character described comprising a plurality of plates respectively having vertical flanges extending lengthwise and across the front end portions of the respective plates, and means for mounting said plates for relative swing- 125
125 ing movement, in combination with a pair of sup-
plemental flanges respectively disposed adjacent to the flanges of their respective cooperating plates, means for movably mounting the respective supplemental flanges on the respective plates, and means operable in accordance with the move-
ment of said plates with relation to each other 130
130 to cause corresponding movement of said sup-
plemental flanges.
135 7. A device of the character described comprising a plurality of plates respectively having vertical flanges, and means for mounting said plates for relative swinging movement, in combination with a pair of supplemental flanges respectively disposed adjacent to the flanges of their cooper- 140
140 ating plates, and means for movably mounting the respective supplemental flanges on the respective plates.
